UNITED STATES PATENT OFFICE.

SAMUEL S. SAMPLINER, OF CLEVELAND, OHIO, ASSIGNEE, BY MESNE ASSIGNMENTS, TO THE RICH-SAMPLINER COMPANY, OF CLEVELAND, OHIO, A CORPORATION OF OHIO.

NECKSCARF OR MUFFLER OR OTHER KNIT GOODS.

1,325,755.

Specification of Letters Patent. Patented Dec. 23, 1919.

Application filed December 6, 1910. Serial No. 595,928.

To all whom it may concern:

Be it known that I, SAMUEL S. SAMPLINER, a citizen of the United States, residing at Cleveland, in the county of Cuyahoga and 5 State of Ohio, have invented certain new and useful Improvements in Neckscars or Mufflers and other Knit Goods, of which the following is a specification.

My invention relates to improvements in 10 knitted articles of wearing apparel, and is set forth more particularly in connection with an improved neck scarf or muffler, with reference, as well, to other garments wherein said invention may be employed.

15 Primarily, my invention relates to the provision in a knitted article of wearing apparel, of an integral semi-elastic edge or border portion, in association with a more loosely knitted and ornamental central or 20 body portion. The utilities of such semi-elastic border or edge are found in the retention of the original shape of the article; the provision of more secure fastening means; a better fit for the knitted article, 25 and straight edges adapted more readily to be stitched together.

My improvement contemplates primarily knitted fabrics produced upon the Lamb flat-knitting machine, wherein the central 30 portion of the knitted article is racked and one or both edges are at the same time knit with the plain chain stitch. This produces a central body portion of looser and more elastic quality, having zigzag series of 35 stitches integrally knitted with straight bordering edges of less elasticity and firmer body.

The principal use to which my invention 40 has been put is in the manufacture of a knitted neck scarf adapted to fit closely about the wearer's neck, by reason of the provision of associated bordering edges and an adjacent elastic section of zigzag stitches. The details of this, together with suggestions 45 for other employment of my invention, will be more readily understood by making reference to the accompanying sheet of drawings, wherein Figure I is a plan view, broken away, showing the neck portion and one 50 end of a neck scarf made in accordance with my invention. Fig. II is a full diagrammatic plan view thereof upon a smaller scale. Fig. III shows such neck scarf or muffler in use. Fig. IV illustrates in fragmentary detail, a modification in connection

with the fastening means for a garment; and Fig. V is a diagrammatic view showing a tubular member, such as a sleeve or protector, made in accordance with my invention. Throughout the several figures of the 60 drawings, I have employed the same character of reference to indicate similar parts.

Referring to Fig. I, it will be seen that the muffler is integrally knit by having the central portion *a* racked in zigzag pattern, 65 while the integral bordering edges *b* are knit perfectly straight, preferably with the chain stitch, to secure a closer texture and make the bordering edges semi-elastic. Preferably, the neck portion is knit with two 70 diagonal sections *c* and a connecting intermediate section *d*, also racked and integral with the straight bordering edges *b*.

It will be appreciated that this neck portion will fit better upon the wearer's neck 75 and over his collar, particularly at the rear thereof, by reason of the conforming elastic section *d* and the close fitting edge *b*, normally drawn closely about the wearer's neck above the edge of said collar. This closely 80 fitting neck is of distinct advantage, since the conforming neck portion guards the opening otherwise formed at the top of a stiff collar. Moreover, the continuous edges *b* maintain the muffler or neck scarf in 85 shape, and may afford, as well, suitable fastening means in the firmer body thereof, as indicated in Fig. IV.

Any desired fastener, of course, may be 90 employed, such as the snap fasteners *e*, shown in the different figures, either located 95 at one side of, or within the body of the bordering edge. The latter feature is illustrated in connection with the neck portion of a garment, Fig. IV, employing a plurality of such fasteners.

Another advantage may be explained in connection with Fig. V, wherein the knitted blank is utilized to form a tubular garment, such as an arm protector or sleeve, having 100 an elastic body portion *a*, formed of the zigzag stitch, as before, with the straight edges *b* sewed together. Previously, it has been necessary to make a zigzag seam in similar garments when the zigzag knitted blank was used, or else the seam was sewed straight and the serrated edges were afterward trimmed off. The blank, Fig. II., is 105 cut on line *x*—*x*, to form this article.

I believe that, prior to my invention, no 110

garments had been made wherein the zig-zag or similar loosely flat knitted body portion as opposed to tubularly knitted goods was integrally knit with a straight edge 5 of closer texture, and accordingly claim as my invention, the following:—

1. In a neck-scarf or muffler, the combination with two patterned end-portions, of a neck - portion intermediate thereof, and 10 elastically - knit, and bordering edges embracing the said neck-portion knitted with a semi-elastic stitch, substantially as set forth.
2. In a knitted neck-scarf or muffler, the 15 combination with two end-portions, of an intermediate neck-portion elastically knit, and a bordering edge therefor of semi-elastic stitch knitted integrally with the foregoing, substantially as set forth.
3. In a continuously knitted neck-scarf or muffler, the combination with two interiorly racked end-portions, of two diagonally extending neck-portions, and an intermediate interiorly racked neck-portion; 25 the said racked portions being knitted with an elastic stitch, and continuous bordering edges knitted with semi-elastic stitches embracing the various portions of the muffler, substantially as set forth.
4. In a neck-scarf or muffler knitted with 30

elastic and semi-elastic portions, the combination with an inelastic or semi-elastic integrally knitted portion extending along the edge, of fastening means connected therewith adjacent to said semi-elastic edge 35 and in the body thereof adapted to secure the elastic portion in position through the meeting semi-elastic edges, substantially as set forth.

5. In an integrally-knit garment, a neck-portion comprising two diagonally-knitted or offset sections and a straight intermediate rear section; the same having an integral semi-elastic bordering upper edge and an adjacent elastic body-portion, substantially as set forth. 40 45

6. In a neck scarf or similar knit garment, a neck-portion formed of a straight rear section and two diagonally extending sections; said sections comprising a continuous bordering upper edge and a more elastic body-portion, integrally knit, and fastening means provided upon the bordering edge, substantially as set forth. 50

In testimony whereof I do now affix my 55 signature in the presence of two witnesses.

SAMUEL S. SAMPLINER. [L. S.]
